UNITED STATES PATENT OFFICE.

ROGER ALEX DEWAR, OF ATLANTA, GEORGIA.

DESIGN FOR A BADGE OR SIMILAR ARTICLE.

49,014.

Specification for Design.

Patented May 9, 1916.

Application filed March 13, 1916. Serial No. 83,978. Term of patent 3½ years.

To all whom it may concern:

Be it known that I, ROGER ALEX DEWAR, a citizen of the United States, residing at Atlanta, in the county of Fulton, State of Georgia, have invented a new, original, and ornamental Design to be Applied to a Badge or Similar Article, of which the following is a specification, reference being had to the accompanying drawing, in which the figure is a view of my new design to be applied to a badge or similar article.

I claim—

The ornamental design to be applied to a badge or similar article, as shown.

ROGER ALEX DEWAR.

Witnesses:

H. B. JONES,

H. L. JOHNSON.
